UNITED STATES PATENT OFFICE.

GEORGE COLEMAN NIXON, OF DETROIT, MICHIGAN, AND FREDERICK CHARLES RAAB, OF SYRACUSE, NEW YORK.

PROCESS OF HARDENING METAL ARTICLES.

1,415,260.

Specification of Letters Patent. Patented May 9, 1922.

Application filed October 25, 1919. Serial No. 333,237.

To all whom it may concern:

Be it known that we, GEORGE COLEMAN NIXON and FREDERICK CHARLES RAAB, citizens of the United States, and residents of Detroit and Syracuse, respectively, counties of Wayne and Salina, respectively, and States of Michigan and New York, respectively, have invented a certain new and useful Process of Hardening Metal Articles; and we do hereby declare that the following is a full, clear, and exact description thereof, reference being had to the accompanying drawings in which like numerals refer to like parts.

15 Our invention relates to the art of carburizing or case hardening iron or steel. In the usual method of preparing articles of steel for carburization, they are placed in a receptacle or pot for holding the carburizing material, which is sealed to prevent access of the air, and the receptacle or pot and the contents thereof are placed in a furnace and heated to a sufficient degree to incorporate the carbon in the surface of the article and thereby case harden it. The receptacle or pot is filled with the carburizing or case hardening material or compound and the metal articles to be treated are embedded therein. Said material or compound as heretofore used has been in dry powder, granular or pellet form, as desired.

30 One difficulty with the foregoing manner of carburizing or case hardening metal articles is the length of time required for treating because the articles are surrounded with a mass of the carburizing material which is difficult for the heat to penetrate, and also because of the lack of intimacy of contact thereof with the metal articles. Also, when the charge has been treated, the pot or receptacle is removed from the furnace and the contents thereof discharged or all allowed to cool with the result that there is a waste of heat.

45 The nature of our improvement in the present invention will be understood from the accompanying drawings and the following description and claims.

In the drawings Fig. 1 is a plan view of a 50 piece of metal in process of being wrapped and covered by the carburizing material in the manner hereafter explained. Fig. 2 is a plan view of a cam shaft with the cams covered with the carburizing material in a 55 modified way, the right hand half being in

section. Fig. 3 is a central vertical section through a pot or receptacle with a cam shaft therein while being heated in a furnace.

The process consists of combining with any suitable carburizing material, in powdered or granular form, material for causing the particles thereof to adhere together and form a plastic mass 10, like putty or dough. This plastic mass may be formed in various ways and by various means as desired. For instance, a twenty per cent mixture of heavy tar or equivalent material with the carburizing material, in powdered or granular form, will produce said plastic material, but the invention is not limited to the means for forming such plastic material.

After the carburizing material has been converted into putty-like plastic form, a tape of carburizing material is formed by taking a relatively narrow strip of burlap or other coarse cloth 11, and uniting with it the plastic material so that the plastic material will lie on both sides of the strip of burlap and pass through its interstices and make a tape-like strip of carburizing material, from one-eighth to one-fourth of an inch thick.

The third step in this process consists in spirally wrapping the metal article, such as the rod 12 with such carburizing material in its tape like form and draw it very tightly as the rod is wrapped so as to cause the carburizing material to come in very close contact with and adhere directly to the surface of the metal. This can be done because of the use of the relatively narrow strip of cloth, as said strip not only holds the carburizing material in tape like form before and as it is being applied to the metal article, but it enables the material to be wrapped tightly around the article and also has a tendency to hold the material on the article during the carburization process. Only such portion of the metal articles as is desired to be carburized is wrapped or covered with the carburizing material.

100 The next step of the process consists in placing the metal article thus wrapped with its individual supply of carburizing material in the pot or receptacle 13, which is sealed by the cap 14, and fine clay or sealing material, and then placed in the furnace and heated in the usual way for carburizing or case hardening the metal.

105 In Figs. 2 and 3 the wrapping or covering of a cam shaft 15 is illustrated. It is wrapped 110

by the same sort of tape construction, with a combination of carburizing material and strip of burlap or other cloth, and then to draw and hold the covering more snugly 5 around the irregularities of such construction as a cam shaft, the same may be bound on the outside by wire 16. When such wire is used it is desirable that the plastic carburizing material should be relatively thick 10 and stiff.

As seen in Fig. 3, which shows the cam shaft in a pot ready for the furnace, the pot is not filled with carburizing material in powdered or granular form as heretofore so 15 as to require a very large percent of unnecessary carburizing material which interferes with and retards the carburization. One metal article as shown is covered with a layer of carburizing material secured to it 20 and there is nothing else in the pot. The result is that the carburization takes place quickly, as there is nothing to interfere with the application of the heat to the material and the metal article, and the carburizing material is in unusually close contact with 25 the metal article as it adheres thereto. Furthermore the metal article can be removed without cooling the pot and another article be put in and thereby there is no loss of heat. 30 In carburizing processes employed heretofore the pot has been taken out of the furnace and cooled for every change. With this process that is not necessary.

It is seen that this process is particularly 35 adapted for carburizing metal articles which

are very irregular in form, and it is also useful when the carburizing material is such as to make it desirable to bind the same with tape 11 or the like upon an article with irregular surfaces.

40

The invention claimed is:

1. The process of carburizing metal, which process includes combining carburizing material in suitable form with a substance that renders it adherent and plastic applying said plastic material to a relatively narrow strip of cloth or the like so as to form a relatively thick tape of carburizing material, wrapping and securing said tape like form of carburizing material spirally on the portion of the 45 article to be carburized, and then heating the article with the carburizing material thus secured thereon.

2. The process of carburizing metal, which process includes combining carburizing material in suitable form with a substance that renders it adherent and plastic, applying said plastic material to a strip of cloth or the like so as to form a relatively thick tape 50 of carburizing material, wrapping and securing said tape-like form of carburizing material spirally on the portion or portions of the article to be carburized, binding the same on its outer side with a fabric and then heating the article with the carburizing material 55 thus secured thereon.

In witness whereof, we have hereunto affixed our signatures.

GEORGE COLEMAN NIXON.
FREDERICK CHARLES RAAB.
